UNITED STATES PATENT OFFICE.

LYMAN SEARL AVERY, OF DALLAS, PENNSYLVANIA, ASSIGNOR OF ONE-
THIRD TO C. D. HONEYWELL, OF SAME PLACE.

THILL-COUPING.

SPECIFICATION forming part of Letters Patent No. 368,505, dated August 16, 1887.

Application filed March 3, 1887. Serial No. 229,517. (No model.)

To all whom it may concern:

Be it known that I, LYMAN SEARL AVERY, of Dallas, in the county of Luzerne and State of Pennsylvania, have invented certain new and useful Improvements in Shaft or Thill Couplings; and I do hereby declare the following to be a full, clear, and exact description of the invention, such as will enable others skilled in the art to which it appertains to make and use 10 the same.

My invention relates to improvements in clips or couplings to attach the thill or tongues to vehicles or conveyances by which they are guided.

15 The object of my invention is the production of a clip or coupling that shall be not only cheap in construction, durable, and easily changed, but afford ample security against accident, such as disconnection or breakage.

20 My invention consists in a short bar, which can be attached to the axle of a carriage in the ordinary manner by loop-bolts, either on the top or underneath, as may be most convenient, having jaws formed upon a projecting end opposite to each other, and extending above and below the projecting end of the bar. Between the jaws, above the bar, is secured the knuckle of the thill-iron by short fixed pins, which project from the sides of the knuckle 25 into holes formed in the above-named jaws. The upper halves of these holes are cut away or opened out and the place supplied by blocks formed on the inside of pieces working in gains cut in the external sides of and pivoted 30 to the lower end of the jaws. These movable pieces and blocks are held securely in position by springs and extend below the pivot in the lower end of the jaws, to afford sufficient leverage to open out these side pieces and 35 blocks over the pins in the knuckle, to allow of the removal or the introduction of the knuckle with its fixed projecting pins through the open space in the upper end of the jaws occupied by the movable blocks. Between 40 the knuckle and the jaw I introduce a spring, either of steel or other elastic substance, which presses the fixed pins which hold the thill-iron in the jaws firmly against one side of the holes to prevent vibration or noise. By this 45 construction there is no probability of derangement by the loss of nuts or bolts, as in the ordinary construction.

That my invention may be the better understood reference is had to the accompanying drawings, in which—

55 Figure 1 represents a side elevation of my improved coupling; Fig. 2, a plan view; Fig. 3, a section through the line 22 in Fig. 2, and Fig. 4 a detail of one of the jaws.

Like figures or letters of reference indicate 60 corresponding parts in all the figures.

1 indicates the short bar, which is securely attached to the axle; 2 and 2', the jaws formed on each side of the bar 1; 3, the knuckle of the thill-iron; 4 and 4', the fixed pins in the knuckle; 65 5 and 5', the movable block formed in connection with the side pieces, 6 and 6'; 7, the extension of the movable pieces 6 and 6', for operating them; 8, the gains cut in the outsides of the jaws, in which the movable side 70 pieces are placed, and secured by the pivot-pin 9; 10, the springs which hold the movable side pieces and blocks in position, and 11 the spring to prevent the vibration and noise occasioned by wear of the pins.

75 Having thus explained my invention, what I claim as new and useful, and desire to secure by Letters Patent, is—

1. In a thill-coupling, the combination of the bar 1, the jaws 2 and 2', formed on the bar 80 projecting above and below with the pivot-holes opened out at the top, the knuckle 3, with its fixed pins 4 and 4', the blocks 5 and 5', formed on the movable side pieces, 6 and 6', with the extension 7 and 7', pivoted to the 85 jaws 2 and 2' by the pins 9, the springs 10, which hold the movable side pieces in position, and the spring 11, to prevent vibration and noise, substantially as and for the purpose set forth.

90 2. In a thill or shaft coupling, the combination, with a bar, 1, having jaws 2 2', of the movable side pieces, 6 6', having blocks 5 5', the pins 9, and springs 10, substantially as and for the purpose specified.

95 In testimony whereof I have hereunto subscribed my name in the presence of two subscribing witnesses.

LYMAN SEARL AVERY.
